(57) **CLAIM**

The ornamental design for a crossbow cam, as shown and described.

DESCRIPTION

FIG. 1 is a perspective view of a first (e.g. right-handed) embodiment of the crossbow cam.

FIG. 2 is a bottom view of the first (e.g. right-handed) embodiment of the crossbow cam.

FIG. 3 is a top view of the first (e.g. right-handed) embodiment of the crossbow cam.

FIG. 4 is a front side view of the first (e.g. right-handed) embodiment of the crossbow cam.

FIG. 5 is a rear side view of the first (e.g. right-handed) embodiment of the crossbow cam.

FIG. 6 is a left side view of the first (e.g. right-handed) embodiment of the crossbow cam.

FIG. 7 is a right side view of the first (e.g. right-handed) embodiment of the crossbow cam.

FIG. 8 is a perspective view of a second (e.g. left-handed) embodiment of the crossbow cam.

FIG. 9 is a bottom view of the second (e.g. left-handed) embodiment of the crossbow cam.

FIG. 10 is a top view of the second (e.g. left-handed) embodiment of the crossbow cam.

FIG. 11 is a front side view of the second (e.g. left-handed) embodiment of the crossbow cam.

FIG. 12 is a rear side view of the second (e.g. left-handed) embodiment of the crossbow cam.

FIG. 13 is a right side view of the second (e.g. left-handed) embodiment of the crossbow cam; and,

FIG. 14 is a left side view of the second (e.g. left-handed) embodiment of the crossbow cam.
